UNITED STATES PATENT OFFICE.

WILLIAM H. GUIWITS, OF RODGERSVILLE, NEW YORK.

SLEIGH.

Specification of Letters Patent No. 12,513, dated March 13, 1855.

To all whom it may concern:

Be it known that I, WILLIAM H. GUIWITS, of Rodgersville, in the county of Steuben and State of New York, have invented a new and useful Improvement in Sleighs, and I do hereby declare that the following is a full and exact description thereof; reference being had to the annexed drawings, forming a part of this specification, in 10 which—

Figure 1, is a side elevation of my improvement. Fig. 2, is a side sectional elevation of the same. Fig. 3, is a view of my improved sleigh turned bottom up.

Similar letters indicate the same parts. A, body part of the sleigh; B, tongue; C, C', axletrees; D, D', runners; E, fifth wheel; F, king bolt; G, G', connecting rod; H, friction wheels; H', friction wheel 20 springs; I, clip in the center of hind axletree; J, J', K, K', L, L, runner braces; M, fixed bolsters; M', M², rolling bolsters; N, N, guide plates of rolling bolsters attached to fixed bolsters M; O, tongue cross 25 bar; P, reach; Q, Q', connecting irons of tongue; R, R, slots in cross bar O.

The body part A, of my improved sleigh is constructed in the usual manner. The tongue B, is secured to the forward runners 30 D, D', by means of the connecting irons Q, Q'. The cross bar serves to stiffen the tongue B, and also to spread the connecting irons Q, Q', which latter pass through slots R, R, in the cross bar O, O. The fastenings 35 of the tongue to the runners are so arranged in connection with the slots R, in the cross bar O, that great freedom of movement in the runners is permitted, without any wrenching of the same, in consequence of 40 their connection with the tongue.

The position of the tongue and appurtenances, when one of the forward runners is elevated by an obstruction in the road, is seen in Fig. 1.

45 The runners D, D, D', D', are secured upon the ends of iron cross bars G, G', which latter are fastened to the underside of the axletrees C, C', and are of the same length. The ends of the cross bars G, G', form bearings for the runners, upon which they turn, each independent of the other.

The forward runners are secured to their bolster by means of the king bolt F, which passes through the axletree C', in the usual

manner. A fifth wheel E, is also provided, 55 so that the forward runners may have perfect freedom to turn, in the manner common to all vehicles.

The hind runners D, D, are provided with 60 rolling bolsters M', M², between which and fixed bolsters M, M, the friction rollers H, H, intervene, the latter being held in their places by the springs H, H', which are fastened in their centers to the top of the hind axletree C.

65 The forward ends of the hind runners D, D, are secured to the reach P, by means of braces L, L. These runners are also further braced by the inner braces K, K, which extend from the forward ends of the runners, back to clip I, on the axletree C, where they fasten.

70 The rolling bolsters M¹, M², are fastened to the axletree C. Owing to the necessary stiffness of the connection of the front ends 75 of the hind runners with the reach P, by the braces L, there could be no independent movement of the hind runners without wrenching the sleigh, unless means were provided for a slight movement of the axletree C, in correspondence with the movements of either of the runners D, D. The arrangement of the rolling bolsters M¹, M², and friction rollers H, H, permit this movement of the axletree, without in the least 80 impairing the stability of the hind runners or any other portion of the sleigh. When the forward end of runner D, is thrown up as in Fig. 2, the hind axletree C, slides back a little; when the forward end of the runner is thrown down, the axletree moves correspondingly forward. In this manner I 85 construct a double runner sleigh having greater flexibility in all its parts, yet of less weight, but more proportionate strength, 90 than any vehicles of the kind ever before made. The cost of construction, in proportion to weight and size, is less, for my improvement than the ordinary sleigh.

95 The flexibility of my sleigh destroys none 100 of its strength, it being capable of sustaining a given burden with equal firmness, whether running over a smooth or rough road. Its great flexibility and freedom from racking also relieves it from sudden jarring 105 or thumping motions, rendering it much more agreeable as a passenger vehicle, than the ordinary sleighs.

Having thus described my invention, I claim,

1. The combination of the sliding bolsters M^1 , M^2 , and friction rollers H , H , with the axletree C , and fixed bolsters M , in the manner, and for the purposes set forth.

2. I also claim the slots R , in cross bar

O , which permit the movement of the forward runners, without any wrenching.

WM. H. GUIWITS.
